SEPARABLE FASTENER

Zeno B. Spence, Goldsboro, N. C.

Application April 8, 1935, Serial No. 15,297

7 Claims. (Cl. 24—227)

My invention relates to a separable fastener structure designed primarily as a combined dust pan suspension, hanger and coupling structure the more particularly a separable fastener for the 5 purpose to be hereinafter referred to.

My invention has for its object to provide, in a manner as hereinafter set forth, a structure of the class referred to for detachably coupling a dust pan in fixed relation to and for suspending it from one side of the head of a broom.

A further object of my invention is to provide, in a manner as hereinafter set forth, a means for detachably connecting a dust pan to one side of a broom head, with the pan so arranged relative to the broom head to prevent any interference with the sweeping action of the broom.

A further object of my invention is to provide, in a manner as hereinafter set forth, means 20 for detachably and firmly suspending a dust pan from one side of a brush head when the pan is not desired for use.

A further object of my invention resides in the providing of, in a manner as hereinafter set forth, a means whereby a dust pan may be carried by a brush head until the pan is desired for use, and with such means so constructed to permit the pan to be expeditiously removed from and connected to the broom head respectively 30 when the pan is to be used and after use.

A further object of my invention is to provide, in a manner as hereinafter set forth, a combined removable dust pan, pan hanger and pan coupler structure of very light weight for 35 attachment to a broom head and of a weight which will not increase the weight of the brush head to an extent to cause a tiresome sweeping action when the broom is used.

Further objects of my invention are to provide, in a manner as hereinafter set forth, a structure for the purpose referred to which is simple in its construction and arrangement, strong, durable, compact, readily installed with respect to a broom head, light in weight, thoroughly efficient in its use and comparatively inexpensive to manufacture.

With the foregoing and other objects in view, my invention consists of such parts and such combination of parts as hereinafter more specifically described and illustrated in the accompanying drawing wherein is shown the preferred embodiment of my invention, but it is to be understood that changes, variations and modifications may be had therein which fall within the 55 scope of the invention as claimed.

In the drawing:

Figure 1 is a side elevation of a broom head with the dust pan detachably connected therewith,

Figure 2 is a view looking towards one edge 5 of the broom and partly in vertical section illustrating the dust pan and hanger and coupler for the dust pan installed,

Figure 3 is an elevation looking towards the side of the broom head shown in Figure 1 with 10 the dust pan removed,

Figure 4 is a section on line 4—4, Figure 3,

Figure 5 is a front elevation of the dust pan,

Figure 6 is a perspective view of the combined hanger and coupler, and

15

Figure 7 is a view upon an enlarged scale looking towards a side edge of the combined latching and suspension element.

The drawing illustrates the head 7 and portion 8 of the handle of a broom, and with reference to Figures 1 and 2, there is shown a dust pan 9 suspendingly supported on the side 10 of head 7. The pan 9 is constructed from any suitable light weight material. The pan is of less length and of less width than the length and 25 width of the side 10. The pan 9 includes a bottom 11 which slightly increases in width from its inner to its outer end, a slightly diverging rim 12 coextensive with the sides and inner end of bottom 11, an outwardly directed flange 13 at 30 the top of and coextensive with rim 12 and a handle 14 in the form of a loop. The stretch 15 of flange 13 arranged on the inner end stretch 16 of the flange is of segmental contour and of greater width than the side stretches of the 35 flange. The handle 14 has forward extensions 17 arranged below and secured to the inner face of stretch 15 by the holdfast means 18. The handle 14 is disposed centrally of stretch 15. The side stretches of rim 12 gradually increase in 40 height from their outer ends to a point outwardly adjacent the points of emergence thereof with stretch 16.

With reference to Figures 2, 3, 4, and 6, there is shown a combined hanger and coupler element or female member 19 of the separable fastener and which is formed of any suitable light weight material. The element 19 includes a U-shaped coupler consisting of a head or base 20 and a pair of bendable arms 21, 22 integral with 50 opposite ends of the head. The arms have pointed ends 23. The element 19 also includes a yoke shaped hanger formed of a head 24 having at its top an outwardly extending guide lip 24a, a pair of sides 25, 26 integral with opposite ends of the 55

head 24 and a pair of oppositely disposed flanges 27, 28 integral respectively with the inner ends of and disposed at right angles to the arms 25, 26. The flanges 27, 28 are anchored to the outer face 5 and are flush with the side and end edges of head 20. The head or front 24 and sides 25, 26 of the hanger coact with the head 20 to provide a vertically disposed passage 29. The hanger may be termed an inwardly opening channel shape 10 part which coacts with the head or base 20 to provide a keeper for a resiliently latching tongue to be referred to.

With reference to Figures 2, 5, and 7, there is shown a resilient combined latching and suspension element 30 which is formed of any suitable light weight material. The element 30 consists of a base 31 and a resilient strap-like extension or member 32 of less width and of materially greater length than that of the base. The inner end 20 of extension or member 32 merges into the upper end edge of base 31. The extension or member consists of an outwardly extending upwardly inclined upper stretch or part 33 merging into a depending inwardly part 34 of compound curvature of a length to extend below the base 31. The part 34 merges at its lower end into a segmental part 35 extending outwardly with respect to part 34. The base 31 is seated against the outer face of bottom 11 of pan 9 in proximity to the stretch 30 16 of rim 12 and is anchored to bottom 11 by the holdfast means 36. The part 33 bears against the outer face of stretch 16 of rim 12. The point of emergence 37 between the parts 34, 35, when the pan 9 is detached, seats against bottom 11. The part 33 constitutes a suspension for pan 9. The parts 34, 35 form the outer stretch of the extension or member 32 and constitute a resilient shift- 35 able frictional latching tongue for firmly securing the pan 9 detachably in position when the latter 40 is coupled to the broom head.

The combined hanger and coupler element 19 is for connection to the head 7 at a point between the transverse median and upper end of the latter. The arms 21, 22 are inserted through the broom head 7 to position head 20 of element 19 45 against the side 10. The arms 21, 22 are of greater length than the thickness of broom head 7 whereby when said arms are extended through the latter they will project from the sides 38 of head 7. The projecting portions of arms 21, 22 50 are bent towards each other and directly against side 38, as shown in Figure 4, thereby anchoring element 19 to head 7. The parts 34, 35 of element 30 are to coact with a wall of passage 29 to frictionally latch the pan 9 with the broom head 7, and in this connection part 34 is extended 55 through passage 29, and as the tendency of said parts 34, 35 is to shift in a direction towards the bottom of the pan 9, it follows that the pan will 60 be held firmly suspended with respect to head 7 when the parts 33, 34 and 35 of element 30 are in the position shown in Figure 2. The part 35 latching the pan and the part 33 coacting with the top of head 24 to suspend the pan. The pan 9 65 is conveniently moved to and from coupled, clamped or latched position by handle 14. If desired the pan 9 may be provided with suitable advertising matter. The lip 24a facilitates the entrance of element 30 into the passage 29.

70 What I claim is:

1. A separable fastener for detachably connecting a dust pan to a broom head, said fastener comprising a male and female member for frictional detachable interengagement, said male member formed of an upstanding base and a re-

silient lateral strap-like extension, said base being apertured for the passage of holdfast means for anchoring it to the front face of a dust pan, said extension being formed of an upper stretch merging into a depending inclined outer stretch, 5 said upper stretch inclining upwardly from the top of said base to the upper end of the outer stretch and constituting a suspension, said outer stretch being of greater height than that of and opposing said base, depending above and below the 10 latter and of compound curvature, providing a resilient latching tongue and disposed in a direction to abut said face when said members are free of interengagement, said female member formed of a yoke having a base for seating 15 against one side of a broom head and a pair of bendable pointed arms for extension through and for bearing against the other side of the broom head whereby the yoke is anchored stationary, said female member including an upstanding in- 20 wardly opening channel shaped part extended laterally from and anchored to the front of said yoke base, said channel-shape part and yoke base coacting to form a keeper for the reception of the latching tongue to provide for the detachable 25 interengagement of said members whereby the dust pan is firmly latched to and suspended from the broom.

2. A separable fastener for detachably connecting a dust pan to a broom head, said fastener 30 comprising a male and female member for frictional detachable interengagement, said male member formed of an upstanding base and a re- 35 silient lateral strap-like extension, said base being apertured for the passage of holdfast means for anchoring it to the front face of a dust pan, said extension being formed of an upper stretch merging into a depending inclined outer stretch, said upper stretch inclining upwardly from the top of 40 said base to the upper end of the outer stretch and constituting a suspension, said outer stretch being of greater height than that of and opposing said base, depending above and below the latter and of compound curvature, providing a resilient latching tongue and disposed in a direction to abut said face when said members are 45 free of interengagement, said female member formed of a yoke having a base for seating against one side of a broom head and a pair of bendable pointed arms for extension through and for bearing 50 against the other side of the broom head whereby the yoke is anchored stationary, said female member including an upstanding inwardly opening channel shaped part extended laterally from and anchored to the front of said yoke base, 55 said channel-shape part and yoke base coacting to form a keeper for the reception of the latching tongue to provide for the detachable interengagement of said members whereby the dust pan is firmly latched to and suspended from the 60 broom, said channel shaped part having the top of its front in the form of an outwardly directed guide lip.

3. A separable fastener for detachably connecting a dust pan to a broom head, said fastener 65 comprising a male and female member for frictional detachable interengagement, said male member formed of an upstanding base and a re- 70 silient lateral strap-like extension, said base being apertured for the passage of holdfast means for anchoring it to the front face of a dust pan, said extension being formed of an upper stretch merging into a depending inclined outer stretch, said upper stretch inclining upwardly from the top of said base to the upper end of the outer 75

stretch and constituting a suspension, said outer stretch being of greater height than that of and opposing said base, depending above and below the latter, and providing a resilient latching 5 tongue and disposed in a direction to abut said face when said members are free of interengagement, said female member formed of a yoke having a base for seating against one side of a broom head and a pair of bendable pointed arms for 10 extension through and for bearing against the other side of the broom head whereby the yoke is anchored stationary, said female member including an upstanding inwardly opening channel shaped part, extended laterally from and anchored to the front of said yoke base, said channel-shaped part and yoke base coacting to form a keeper for the reception of the latching tongue to provide for the detachable interengagement 15 of said members whereby the dust pan is firmly latched to and suspended from the broom.

4. A separable fastener for detachably connecting a dust pan to a broom head, said fastener comprising a male and female member for frictional detachable interengagement, said male member formed of an upstanding base and a resilient lateral strap-like extension, said base being apertured for the passage of holdfast means for anchoring it to the front face of a dust pan, said extension being formed of an upper stretch merging into a depending inclined outer stretch, said upper stretch inclining upwardly from the top of said base to the upper end of the outer stretch and constituting a suspension, said outer stretch being of greater height than that of and opposing 30 said base, depending above and below the latter, and providing a resilient latching tongue and disposed in a direction to abut said face when said members are free of interengagement, said female member formed of a yoke having a base 35 for seating against one side of a broom head and a pair of bendable pointed arms for extension through and for bearing against the other side of the broom head whereby the yoke is anchored stationary, said female member including an up- 40 standing inwardly opening channel shaped part extended laterally from and anchored to the front of said yoke base, said channel-shaped part and yoke base coacting to form a keeper for the reception of the latching tongue to provide for the de- 45 tachable interengagement of said members whereby the dust pan is firmly latched to and suspended from the broom, said channel shaped part having the top of its front in the form of an outwardly directed guide lip.

5. In a separable fastener for detachably connecting a dust pan to a broom head, an apertured base adapted to be positioned against the upper end of the front face of the pan, holdfast means extending through said base for anchoring the latter to said front face, a resilient lateral extension of strap-like form provided with an upper and an outer stretch, said upper stretch being integral at one end with the top of the base and at its other end with the upper end of the outer stretch, said upper stretch inclining upwardly from said base to said outer stretch, said outer stretch being of compound curvature, opposing and extending above and below said base, extending towards and adapted for releasably abutting said front face below said base and constituting a shiftable latching tongue for frictional binding engagement with the broom head.

6. In a separable fastener for detachably connecting a broom to a dust pan, a yoke including a base adapted to abut one side of the broom head and a pair of pointed bendable arms adapted to extend through and bendable for abutting the other side of the broom head for anchoring the yoke thereto, an inwardly opening vertically disposed channel shaped part abutting and extending laterally from the front face of said base, said part being formed at its sides with oppositely extending flanges anchored to the front face of said base adjacent said sides, said part and yoke providing a keeper adapted for frictional engagement with a latching tongue adapted to be carried by a dust pan whereby the latter is coupled to the broom head.

7. In a separable fastener for detachably connecting a dust pan to a broom head, a male member adapted to be carried by the dust pan for frictional detachable interengagement with a female member adapted to be carried by a broom head, said male member including a base adapted to be anchored to the dust pan and a resilient lateral extension of strap-like form provided with an upper and an outer stretch, said upper stretch being integral at one end with the top of said base and at the other end with the upper end of said outer stretch, said upper stretch inclining upwardly from said base to said outer stretch, said outer stretch being of compound curvature, opposing and extending above and below said base, extending towards and releasably abutting said dust pan and constituting a shiftable latching tongue for frictional binding engagement with the female member.

ZENO B. SPENCE.
